COMBINED SPACE CONDITION CONTROL AND WEATHER INDICATING INSTRUMENT

Henry Dreyfuss, South Pasadena, Calif., assignor to Minneapolis-Honeywell Regulator Company, Minneapolis, Minn., a corporation of Delaware

Filed Sept. 24, 1959, Ser. No. 57,664

Term of patent 14 years

(Cl. D52—7)

Fig. 1

Fig. 2

Figure 1 is a front perspective view of a combined space condition control and weather indicating instrument embodying my new design; and

Figure 2 is a side elevational view in cross section looking in the direction of the arrows on line 2—2 of Figure 1.

The essential features of the design reside in the panel portion shown in full lines.

I claim:

The ornamental design for a combined space condition control and weather indicating instrument, substantially as shown and described.
